(57) **CLAIM**

The ornamental design for a belt having removable beverage bottles, as shown.

DESCRIPTION

FIG. 1 is a perspective view of a belt having removable beverage bottles showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side view thereof;

FIG. 7 is a view of the opposite side thereof;

FIG. 8 is a perspective view of a modified form of our design;

FIG. 9 is a front elevational view thereof;

FIG. 10 is a rear elevational view thereof;

FIG. 11 is a top plan view thereof;

FIG. 12 is a bottom plan view thereof;

FIG. 13 is a side view thereof;

FIG. 14 is a view of the opposite side thereof;

FIG. 15 is a perspective view of another embodiment of our design;

FIG. 16 is a front elevational view thereof;

FIG. 17 is a rear elevational view thereof;

FIG. 18 is a top plan view thereof;

FIG. 19 is a bottom plan view thereof;

FIG. 20 is a side view thereof;

FIG. 21 is a view of the opposite side thereof;

FIG. 22 is a perspective view of still another embodiment of our design;

FIG. 23 is a front elevational view thereof;

FIG. 24 is a rear elevational view thereof;

FIG. 25 is a top plan view thereof;

FIG. 26 is a bottom plan view thereof;
FIG. 27 is a side view thereof; and,
FIG. 28 is a view of the opposite side thereof.
